COMBINED AUTOMOBILE FOOT-RAIL AND
UMBRELLA RECEPTACLE

Edmund Daniele, Astoria, N. Y., assignor of one-half to Alfred H. Bamberger, New York, N. Y.

Application April 22, 1933, Serial No. 667,374

5 Claims. (Cl. 296—75)

This invention relates to automobile equipment and more particularly to an improved foot-rail which is also utilized as a receptacle for the storage of an umbrella. The object of the invention is to provide a simple and convenient means for storing an umbrella in an automobile of the class in which foot-rails are provided for the comfort of passengers, where such umbrella will not interfere with the comfort of the passengers or injure the interior of the automobile when the same is not in use and which, when the umbrella is contained therein, will be free from noise or vibration when the automobile is in motion. A further object of the invention is to provide a combined foot-rail and umbrella holder, such that the umbrella is readily removable from and insertable into the improved foot-rail, such combined structure harmonizing with the standard equipment of the automobile, while effectively concealing the umbrella from view and not taking up appreciably more space than the standard foot-rail.

As far as I am aware, automobiles have not heretofore been provided with convenient receptacles for the storage of umbrellas in such manner as not to take up room in the already limited space of the vehicle, and to be free from noise and vibration when the vehicle is in motion. Generally umbrellas are placed in some inconvenient place such as the seat or floor, where they interfere with the comfort of the passengers. This is especially so when the umbrella is wet, when in addition to the discomfort, the interior upholstery of the car is subject to being stained and rotted by dampness. All of the above is a common experience with automobile owners and the device of the present application was designed to overcome all such inconveniences. Essentially my device consists of a hollow foot-rail which may be pivotally mounted on the floor board of the automobile, as is the common practice, and which is provided with removable ends, one of which may form part of the handle on an umbrella adapted to be inserted inside the hollow foot-rail. This end portion, which has a short sleeve adapted to engage snugly the inner periphery of the hollow foot-rail, may be made of metal similar to that of which the foot-rail is constructed or of a lighter metal or other material and is preferably so designed that it appears to be part of the foot-rail and is harmonious in design therewith, and preferably has no protruding portions which are likely to be dangerous to the passengers. To this end portion is attached in any suitable manner the remainder of the um-

brella handle which may be made of wood, bone, resin, or any other suitable material, as is common in umbrella handles, and may be so designed that it snugly engages the inner periphery of the hollow foot-rail and together with the end portion when in use will give a pleasing appearance. The umbrella to which the handle is attached may be a gentlemen's or ladies' size, and the rail should be of such bore that the umbrella fits snugly inside such rail, so that the metal tip or foot at the end of the umbrella opposite the handle will be prevented from rattling against the inner wall of the hollow foot-rail. The umbrella may be readily removed from its receptacle by pulling outwardly on the removable end portion. To replace the umbrella, it is only necessary to wind the frame and cloth portion tightly about the central rod and insert it into the hollow rail, if desired with a slight turning movement. Vents may also be provided at suitable places in the rail in order that currents of air may have access to the interior of the rail to dry out a damp umbrella and keep it from rotting. The remaining space in the hollow foot-rail may be used for the purpose of storing rubbers, cloths, etc., in which case I provide a hollow sleeve adapted to fit snugly inside of the hollow rail, such sleeve being attached to or integral with the other removable end of the foot-rail and provided with an aperture of such size that the inserted rubbers or cloths cooperate to prevent rattling or vibration thereof while the car is in motion, as will be hereinafter explained.

The invention is illustrated by way of example in the accompanying drawing in which Fig. 1 represents a plan view of the body portion of an automobile with the top removed and provided with a foot-rail in accordance with the invention, the umbrella being shown as partially withdrawn from the rail; Fig. 2 is an enlarged view of my improved foot-rail, the same being shown partially broken away and in section; Fig. 3 is a detail view of the receptacle adapted to be inserted in one end of the foot-rail; and Fig. 4 is a section on line 4—4 of Fig. 2.

Referring to the drawing, the numeral 1 indicates an automobile of the class in which a foot-rail 2 is provided for the comfort of the passengers. The foot-rail 2, which consists of a long hollow cylinder of relatively small diameter, is supported adjacent to each end on the vertically disposed portions 3 of the arms 4, in any suitable manner. The other ends of the arms 4 are rotatably mounted on pins 5 suitably supported in bearings 6 fixed to the floor 7 of the automobile.

by the screws or bolts 8. A projection 9 on each of the arms 4 supports the arm proper at a definite elevation with respect to the floor 7 of the automobile, thus maintaining the foot-rail 2 in its operative position at a convenient distance from the floor. By such mounting, which is usual in cars of this class, the foot-rail 2 may be swung out of place toward the rear seat as shown in dotted lines in Fig. 4.

10 Forming part of the exterior design of the foot-rail 2 are the removable ends 10 and 11 which may be made of metal similar to that of which the foot-rail 2 is constructed or of a lighter metal or other material. The end portion 10 has a 15 short sleeve 12 of such exterior diameter that it is in close contact with the inner periphery of the hollow foot-rail 2. The sleeve 12 surrounds and is fixedly attached, in any suitable manner, to the reduced end portion of a cylindrical umbrella 20 handle 13, the latter of which is of the same diameter as the sleeve 12, so that it snugly engages the inner periphery of the hollow foot-rail. Thus the sleeve 12 of the removable end 10 and the cylindrical portion 13 together form the handle 25 of an umbrella 14 which fits snugly inside of the hollow foot-rail in such a manner as to prevent vibration between the parts, yet may be drawn quite readily from within the foot-rail. The part 13 of the handle may be made of wood, 30 bone or any other suitable material, such as is common in umbrella handles, and of any suitable color, so that together with the removable end 10 it presents a pleasing appearance. The umbrella 14 which may be a gentlemen's or ladies' size, is of 35 such a size when wound tightly about the central rod as to fit snugly inside of the hollow foot-rail, so that the foot or tip portion 15 thereof will not come into contact with the inner wall of the hollow foot-rail 2, thus preventing noisy contact 40 therewith while the car is in motion. Thus, by the combination of elements above described, an umbrella may be conveniently stored away when not in use, in such a manner that it is not in the way of the passengers and at the same time is 45 prevented from rattling, regardless of the amount of vibration caused by the engine or by the movement of the car.

In a further development of my invention, the end 11 is also made removable and is provided 50 with a receptacle 16 integral with said end or attached thereto in any suitable manner, and of such length as to accommodate a pair of rubbers, cleaning cloths, chamois, etc. The exterior diameter of the receptacle is such that it is in close 55 contact with the inner wall of the hollow foot-rail 2, but may be readily withdrawn therefrom and subsequently reinserted. An elongated aperture 17 is provided in the sleeve 16 so that the rubbers, cloths, etc. may readily be placed therein, 60 such aperture at the same time enabling the rubbers, cloths, etc. tightly packed therein to bear against the inner wall of the foot-rail when the receptacle 16 is inserted in the latter to prevent rattling of the receptacle 16 and the end 11 65 against the inner side of the foot-rail 2. The end portion of the receptacle 16 may be slotted, as at 18, and the ends caused to bend or spring outwardly to give such portion a slightly greater external diameter than the internal diameter of the 70 rail in order that such end portion may fit tightly against the inner periphery of the foot-rail, thereby further insuring against rattling or vibration of the receptacle 16 within the foot-rail.

Apertures 19 may be provided at suitable places 75 in the foot-rail 2 to enable currents of air to pass

through the interior of the rail to dry out a wet umbrella, cloth, rubbers, etc. and keep the interior of the foot-rail dry and thereby preserve the umbrella, rubbers, cloths, etc. against rotting.

I claim:

1. In a passenger vehicle the combination of a rigid hollow cylinder having a length substantially greater than that of an ordinary umbrella and having an inner dimension approximately equal to the peripheral dimension of the fabric part of an ordinary umbrella when rolled up, means for permanently attaching the cylinder to the vehicle body and for supporting said cylinder closely above and out of contact with any part of the floor of the vehicle in position to serve as a foot support for passengers seated in the vehicle and in registry with a doorway of the vehicle, an umbrella adapted to be fitted within said cylinder through the end of the latter which is adjacent to the doorway of the vehicle and comprising a handle, a rod terminating in a tip, ribs and fabric, the fabric sections thereof being in rolled condition and in pressure contact with the inner periphery of the cylinder thereby maintaining the tip portion of the umbrella which is positioned within the cylinder at a point remote from the other end thereof, out of all contact with any part of the inner wall of said cylinder, the handle of the umbrella comprising a stubby portion adapted to slidably fit within the end portion of the cylinder adjacent to the doorway of the vehicle and snugly contacting with the inner wall of said end portion of the cylinder, preventing vibration therebetween, said handle including an enlarged head portion positioned exteriorly of said cylinder and being harmonious therewith and adapted to supply the terminal configuration of the closure for the open end of the cylinder when the umbrella is positioned therein so that no umbrella structure as such is visible without the confines of said cylinder, said head portion projecting from the cylinder to a limited extent only so that when the weight of a passenger is placed upon said projecting portion no strain deleterious to any part of the umbrella structure is developed but said strain is transmitted through the stubby portion of the handle and thence through the cylinder and its supports to the body of the vehicle whereby deformation of said open end of the cylinder and all tendency of the handle to break between its said head portion and the portion seated within the cylinder is prevented, said head portion being also adapted to be grasped for removing the umbrella from and for properly positioning the umbrella within said cylinder. 55

2. In a passenger vehicle the combination of a rigid hollow cylinder arranged transversely of the vehicle in registry with a doorway thereof and adapted to serve as a foot support for passengers seated in said vehicle, an umbrella having a length 60 substantially shorter than that of said cylinder and adapted to be fitted within said cylinder when in rolled condition through the end of the latter which is adjacent to the doorway of the vehicle, said umbrella comprising a handle, a rod terminating in a tip, ribs and fabric, the fabric sections thereof being in pressure contact with the inner periphery of the cylinder so that the tip of said umbrella is maintained out of contact with the cylinder at all times, the handle of said umbrella comprising a stubby portion adapted to fit within the cylinder and an enlarged portion having a cross sectional area at least equal to that of the cylinder and adapted to supply the terminal configuration of the closure for said end of 70 75

the cylinder when the umbrella is positioned therein, the stubby portion of said handle snugly contacting with the inner wall of said cylinder preventing vibration therebetween and the enlarged portion of said handle being substantially shorter along its axis than the stubby portion and projecting from the cylinder to a limited extent only so that the leverage on the end of the cylinder of any force acting on a side surface of said portion is relatively small.

3. The combination set forth in claim 1 in which the cylinder is metallic and the stubby portion of the umbrella handle comprises a non-metal member permanently attached to the umbrella rod and having a reduced portion near its outer end and a metal collar encircling the reduced portion in a permanent manner and forming a surface of such periphery as to snugly engage the inner wall of the foot rail cylinder and to

20 25 form a metal to metal contact therewith.

4. The combination set forth in claim 1 in which the cylinder is metallic and the stubby portion of the umbrella handle comprises a non-metal member permanently attached to the umbrella rod and having a reduced portion near its outer end and a metal cap mounted on said reduced por-

tion and a collar attached to said cap, said collar encircling the reduced portion in a permanent manner and forming together with the remainder of said stubby member a surface of such periphery as to snugly engage the inner wall of the foot rail cylinder both with respect to the non-metal as well as to the metal collar portion of the stubby member.

5. The combination set forth in claim 1 in which the end of the cylinder remote from the umbrella handle includes a removable closure having an end portion corresponding in configuration to the protruding head portion of the umbrella handle and a hollow cylindrical body portion of such diameter that the exterior surface thereof snugly engages with the inner wall of the foot rail cylinder, said body portion having an aperture adapted for the reception of compressible articles such as rubber overshoes which by reason of their compressible characteristics bear against that portion of the inner wall of the foot rail cylinder adjacent to said aperture and counteract any tendency to cause rattling and assist in preserving the position within the cylinder of the removable closure.
